UNITED STATES PATENT OFFICE.

ROY S. THOMPSON, OF CHICAGO, ILLINOIS.

INTERNAL-COMBUSTION ENGINE.

No. 878,578.

Specification of Letters Patent.

Patented Feb. 11, 1908.

Application filed April 2, 1907. Serial No. 365,983.

To all whom it may concern:

Be it known that I, ROY S. THOMPSON, a citizen of the United States, and a resident of Chicago, in the county of Cook and State of Illinois, have invented a new and Improved Internal-Combustion Engine, of which the following is a full, clear, and exact description.

This invention relates to certain improvements in internal combustion engines, and more particularly to means whereby an explosion may be obtained in the cylinder at every revolution of the crank shaft and the cylinder completely scavenged of the exhaust gases before each fresh charge is admitted.

My invention relates more especially to means whereby two cylinders may be used in conjunction, one end of each cylinder constituting the compression chamber and the other end of each cylinder constituting the explosion or working chamber, and the two cylinders so connected together that the gas compressed in one cylinder is transferred to the other cylinder and after being ignited is employed for operating the piston therein. In this manner I deliver two impulses to the crank shaft during each revolution thereof, and simultaneously compress the gas to as high a point as may be desired before igniting the same; all by the use of but two cylinders constructed and operated as herein set forth described.

The invention consists in certain features of construction and combination of parts, all of which will be fully set forth hereinafter and particularly pointed out in the claims.

Reference is to be had to the accompanying drawings forming a part of this specification, in which similar characters of reference indicate corresponding parts in all the figures, and in which

Figure 1 is a plan view of an engine constructed according to my invention, a portion of each fly wheel and a portion of the inlet conduit being broken away; Fig. 2 is a side elevation of my improved engine, one fly wheel being removed; Fig. 3 is an end view; Fig. 4 is a central horizontal section through the two cylinders and the cooperating parts; Fig. 5 is a central vertical section through one of the cylinder heads and the cooperating port-controlling member; Fig. 6 is an end view of the port-controlling member shown in Fig. 5; Fig. 7 is a section similar to Fig. 5 but taken through the other cylinder; Fig. 8 is a view similar to Fig. 6, but illustrating the port-controlling member used

in connection with the second cylinder; and Fig. 9 is a diagrammatic section illustrating more completely the arrangement of ports and passages and the method of operation.

In my improved engine I provide two cylinders 10 and 11 mounted upon a suitable frame 12 and having pistons 13 and 14 mounted therein and operatively connected to the crank shaft 15. In each cylinder are preferably provided journal pins 16 cast integral therewith if desired and mounted to oscillate within suitable journal boxes 17 supported by the main frame 12 of the engine. All of these journal boxes are mounted in alinement and the two cylinders are so mounted that they may oscillate upon the journal pins as the pistons reciprocate. The crank shaft 15 is mounted within journal boxes 18 at the opposite end of the engine frame and is provided with two cranks 19 set at an angle of 180 degrees to each other, whereby the pistons 13 and 14 which are operatively connected thereto by the piston rods 20 may move in unison but always in the opposite direction. The crank shaft 15 supports a fly wheel 21 upon one end thereof and any suitable means, as, for instance, a pulley 22 may be mounted upon the opposite end, whereby the power generated may be utilized for any desired purpose. The cylinders may be cooled in any suitable manner, as, for instance, by means of water jackets, or as shown by means of radiating flanges 23 surrounding the same and serving to radiate the heat to the atmosphere. The oscillation of the cylinders serves to cause a circulation of air and this aids in the cooling effect. Each cylinder is provided with a detachable cylinder head 24 rigidly secured thereto and supporting a suitable packing box 25 surrounding the corresponding piston rod 20.

For controlling the flow of fluids to and from the cylinders, I provide the head of each cylinder adjacent the journal pins 16 with a semi-cylindrical section 26 having its outer surface lying in the arc of a circle having a center with the journal pins 16. The surface of this semi-cylindrical portion 26 thus remains in the arc of the same circle at all times during the oscillation of the cylinder. Extending through the cylinder head and the semi-cylindrical portion or curved section 26, I provide a passage 27 leading from the interior of the adjacent end of the cylinder to the curved surface and extending longitudinally through the wall

- of the cylinder and the curved section, and communicating with the cylinder at its opposite end I provide a passage or conduit 28 also leading to a point on the curved surface. 5 The two cylinders 10 and 11 are constructed exactly alike, except that the passage 28 of the first of these cylinders extends along the under side thereof, while the corresponding passage of the other cylinder extends along 10 the upper side. The passages or conduits 27 serve to permit the entrance of the expanded gas to the working space of the cylinders and permit the escape of the exhaust gases therefrom, while the passages or conduits 28 serve for the delivery of the explosive mixture to the opposite or compression end of each cylinder and the escape of the charge after it has been compressed 15 therein.
- 20 Mounted within the engine frame and in engagement with the curved end of each cylinder, I provide two port-controlling members 29 and 30, each having a concave surface adapted to fit and engage with the curved surface of the section 26 of the corresponding cylinder. Each of the port-controlling members is provided with a plurality of passages leading to and from the concave surface and adapted to communicate with the 25 passages 27 and 28 of the cylinders as the latter are oscillated. Each port-controlling member is provided with two passages adapted to communicate with the corresponding passage 27 and two passages 30 adapted to communicate with the corresponding passage 28, and these several passages of one port-controlling member are connected to those of the other, as will be hereinafter described. Each port-controlling member is preferably circular in vertical 35 section and is mounted within a cylindrical recess in the engine frame, means being provided for moving the member within said recess and holding it resiliently in engagement with the end of the corresponding cylinder. As shown, the engine frame is provided with flanges 31 holding the port-controlling members from lateral movement and a suitable yoke 32 is provided having 40 one end thereof in engagement with each of the port-controlling members adjacent its center and having a centrally disposed bolt 33 passing through an opening in the engine frame. A suitable nut 34 is provided 45 for the inner end of the bolt and between this nut and the engine frame I provide a strong coil spring 35 tending to draw the yoke into firm engagement with both of the port-controlling members and holding said 50 members in firm engagement with the ends of their respective cylinders. The port-controlling member 30 is provided with a passage 36 leading from the upper surface thereof to such a point on the concave surface 55 that it may register with the passage 28 when the opposite end of the cylinder 11 is moved to a position below the level of the journal pins, but be prevented from registering therewith when the cylinder is in a horizontal position or the opposite end of 60 the cylinder is raised. The port-controlling member 30 is also provided with a passage 37 leading from the outer flat surface to such a point on the concave surface that it communicates with the passage 28 of the cylinder 11 when the opposite end of the cylinder is raised above the horizontal. The lower portion of the port-controlling member 30 is provided with a passage 38 communicating with the passage 27 of the cylinder when the opposite end of said cylinder is below the horizontal, and below the passage 38 is a passage 39 communicating with the passage 27 of the cylinder when the opposite end of 65 the latter is raised. 75
- 80 The passages of the port-controlling member 29 are somewhat similar to those of the member 30, but extend in a somewhat different direction due to the differences in the relative locations of the passages 27 and 28 of the cylinder 10. The passage 36^a of the port-controlling member 29 leads from the top of the member to such a point that it may communicate with a passage 28 of the cylinder 10 when the opposite end of the latter is depressed, thus operating similarly to the passage 36 of the member 30. The passage 37^a corresponds with the passage 37 of the other member but leads to the bottom of the member rather than to the flat outer 85 surface thereof. The passage 38^a leads from a point on the surface of the member 30 exactly corresponding to the outlet from the passage 38 but leading to the upper portion of the member where it may communicate 90 with the passage 27 of the cylinder. The passage 39^a of the member 29 corresponds to the passage 39 of the member 30 but leads to the upper portion of the flat outer surface rather than to the bottom of the member as 95 does the passage 39. 100
- 100 A suitable conduit 40 is provided having radiating flanges 41 and having its ends so constructed that it may be readily secured to the flat surface of each of the members 29 and 30 and place the passage 37 of the member 30 in communication with the passage 39^a of the member 29. A second conduit 42 is provided similar to the conduit 40 and also having radiating flanges and means whereby 11 it may be secured to the members 29 and 30. This conduit 42 is secured to the lower curved surface of each member and serves to place the passage 39 of the member 30 in communication with the passage 37^a of the member 29. Each of these conduits is provided with a suitable opening 43 in which is secured any suitable form of igniter, as, for instance, a spark plug. Disposed directly below the conduit 40 and somewhat similar thereto I 12
- 125

provide a conduit 44 rigidly secured to each of the port-controlling members and communicating with the conduits 38 and 38^a. Intermediate the ends of this conduit I provide a suitable branch 45 serving as a common exhaust from both cylinders. Bisected diametrically opposite from the conduit 42 is a conduit 46 communicating with the passages 36 and 36^a and having a branch 10 47 serving as a common inlet for the two cylinders.

In order to more clearly illustrate the operation of my improved engine, I have shown in Fig. 9 of the drawings a diagrammatic representation of the cylinders, port-controlling members and the several conduits, and in order that the corresponding portions may be readily identified, the same reference characters have been applied. With the parts in the position illustrated in the diagram, a movement of the crank shaft would draw the piston 13 toward the left-hand end of the cylinder and would raise the outer end. This inclination of the cylinder would place the port 27 of the cylinder 10 in communication with the passage 39^a and would place the passage 28 of this cylinder in communication with the passage 37^a. At this time the gas within the conduit 40 is ignited and the pressure is communicated directly to the piston and it is forced toward the outer end. This outward movement of the piston compresses the gas in the space between it and the head 24 and the compressed gas passes out the passages 28 and 37^a into the conduit 42. As the piston reaches the end of its stroke the cylinder is again returned to the position indicated in the diagram, and a further movement of the crank shaft lowers the outer end of the cylinder below the horizontal, and the passage 27 is placed in communication with the passage 38^a and the passage 28 is placed in communication with the passage 36^a. The piston in traveling through the return stroke draws in a fresh supply of uncompressed explosive mixture through the conduits 47 and 46 and passages 36 and 28, and the exhaust gas in the opposite end of the cylinder is forced out through the passages 27 and 38^a and the conduits 44 and 45. Upon completing the cycle the parts are again in the position indicated in Fig. 3 and the process is repeated. Meanwhile, a similar series of steps has been going on in the cylinder 11. The gas compressed in this cylinder and forced out through the passage 28 is delivered to the conduit 40 to be ignited and utilized in the cylinder 10, and the gas compressed into 60 the conduit 42 by the piston 13 in the cylinder 10 is ignited and expanded against the piston 14 of the cylinder 11. As will be seen, at each revolution of the crank shaft, two explosions take place, one in the conduit 42 when the latter is in communication with the

cylinder 11, and the other in the conduit 40 when it is in communication with the cylinder 10. Two impulses are thus given to the crank shaft, and at each working stroke of each piston the charge of explosive mixture is compressed for delivery to the opposite cylinder.

The passage of gas to and from each end of each cylinder is controlled entirely automatically, there being no complicated valve mechanism to stick or get out of order. As will be noted, it is impossible for the crank shaft to turn without effecting a corresponding oscillation of both of the cylinders, and this oscillation must necessarily result in the opening or closing of the proper ports. The time at which the various ports are opened or closed may be readily controlled by varying the location of the ends of the corresponding passages of the curved surfaces, and the extent to which the gas is compressed may be readily controlled by varying the size or the location of the conduits 40 and 42, inasmuch as substantially the entire compressed charge is held within these conduits until the port leading to the proper cylinder is opened and the compressed charge is ignited.

It is evident that the cylinders need not be arranged in parallel but may, if desired, be arranged in alinement and connected to separate crank shafts, but the illustrated construction appears to be preferable.

Various changes may be made in the form and construction and within the scope of the appended claims, but without departing from the spirit of my invention.

Having thus described my invention, I claim as new and desire to secure by Letters Patent:

1. An internal combustion engine, comprising a movable cylinder, a piston operating therein, said cylinder having a passage communicating with each end thereof, and a stationary port-controlling member in engagement with said cylinder and having two separate conduits adapted to communicate with each of said passages, the communication between said passages and said conduits being determined by the position of said cylinder.

2. An internal combustion engine, comprising a plurality of cylinders, a piston operatively mounted within each cylinder; each of said pistons adapted to compress a fuel charge upon one side of the piston and to be moved by the ignition of a fuel charge upon the opposite side thereof; means for delivering the fuel charge compressed within each cylinder to another cylinder upon the ignition side of the piston thereof and a port-controlling member for each cylinder for controlling the admission and exhaust of gas from both ends thereof.

3. An internal combustion engine, comprising a plurality of cylinders, pistons to-

cated therein and adapted to compress a fuel charge upon one side thereof and be moved by the ignition of a fuel charge upon the opposite side thereof, means connecting said 5 pistons whereby they operate simultaneously, one piston being upon the exhaust stroke at the time another piston is upon the explosion and compression stroke, means whereby the fuel charge compressed in the 10 compression space of each cylinder is delivered to be ignited in another cylinder and a port-controlling member for each cylinder for controlling the admission and exhaust of 15 gas from both ends thereof.

15 4. An internal combustion engine, comprising a plurality of cylinders, each having a piston operating therein, means connecting said pistons whereby they operate simultaneously, each of said cylinders having a passage 20 communicating with each end thereof, and a plurality of conduits adapted to communicate with each of said passages, said conduits being so arranged that gas compressed in one end of each cylinder may be 25 delivered to the opposite end of another cylinder.

5. An internal combustion engine, comprising two cylinders, pistons operating therein, means connecting said pistons 30 whereby they operate simultaneously, each of said cylinders having separate passages leading to the opposite ends thereof, a port-controlling member in engagement with each cylinder and having separate passages adapted 35 to be placed in communication with the passages of the cylinder, and a plurality of conduits connecting said port-controlling members, whereby the fuel charge compressed in one cylinder may be delivered for 40 ignition against the piston of the other cylinder.

6. An internal combustion engine, comprising two pivotally mounted cylinders, pistons operating therein, means whereby 45 said pistons operate simultaneously in opposite directions, each of said cylinders having passages communicating with each end thereof, means whereby the oscillation of each cylinder controls the flow of gas through 50 said passages, and conduits connecting each end of each cylinder with the opposite end of the other cylinder.

7. An internal combustion engine, comprising a plurality of pivotally mounted cylinders, each having a piston operating 55 therein, means connecting said pistons whereby they operate simultaneously, each of said cylinders having a passage communicating with each end thereof, and two separate conduits adapted to communicate with each of said passages, said conduits being so arranged that gas compressed in one end of each cylinder may be delivered to the opposite end of another cylinder.

8. An internal combustion engine, com-

prising a plurality of pivotally mounted cylinders, each having a piston operating therein, means connecting said pistons whereby they operate simultaneously, each of said cylinders having a passage communicating with each end thereof, and two separate conduits adapted to communicate with each of said passages, said conduits being so arranged that gas compressed in one end of each cylinder may be delivered to the opposite end of another cylinder, the communication between the passages of the cylinders and said conduits being controlled by the oscillation of 70 said cylinders. 75

9. An internal combustion engine, comprising two cylinders, pistons operating therein, means connecting said pistons whereby they operate simultaneously, each of said cylinders having a separate passage communicating with the opposite ends 80 thereof, two conduits connecting said passages whereby gas compressed in one end of one cylinder may be delivered to the opposite end of the other cylinder, and an igniter 85 in communication with each of said conduits. 90

10. An internal combustion engine, comprising two pivotally mounted cylinders, pistons operating therein, means connecting said pistons whereby they operate simultaneously, each of said cylinders having separate 95 passages leading to the opposite ends thereof, a port-controlling member in engagement with one end of each cylinder and having separate passages adapted to be placed in communication with the passages of the 100 cylinders by the oscillation of the latter, and conduits connecting said port-controlling members.

11. An internal combustion engine, comprising two pivotally mounted cylinders, 105 pistons operating therein, means connecting said pistons whereby they operate simultaneously, each of said cylinders having separate passages leading to the opposite ends thereof, a port-controlling member in 110 engagement with one end of each cylinder and having separate passages adapted to be placed in communication with the passages of the cylinders by the oscillation of the latter, conduits connecting said port-controlling members, whereby gas compressed in one end of one cylinder may be delivered to the opposite end of the other cylinder, and 115 an igniter in each of said conduits.

12. An internal combustion engine, comprising a pivotally mounted cylinder having a curved section adjacent the pivotal support, said cylinder being provided with separate passages leading from the opposite ends thereof to the curved surface of said 120 curved portion, and a port-controlling member having a plurality of passages therein adapted to be placed in communication with the passages of said cylinder by the oscillation of the latter. 125

13. An internal combustion engine, comprising a pivotally mounted cylinder having a curved section adjacent the pivotal support, said cylinder being provided with 5 separate passages leading from the opposite ends thereof to the curved surface of said curved portion, a port-controlling member having a plurality of passages therein adapted to be placed in communication with the 10 passages of said cylinder by the oscillation

of the latter, and means for resiliently supporting said port-controlling member.

In testimony whereof I have signed my name to this specification in the presence of two subscribing witnesses.

ROY S. THOMPSON.
